COIN PURSE

William H. St. Thomas, Gloversville, N. Y., assignor to St. Thomas Inc., Gloversville, N. Y., a corporation of New York

Application January 29, 1952, Serial No. 18,277

Term of patent 7 years

(Cl. D87—3)

To all whom it may concern:

Be it known that I, William H. St. Thomas, a citizen of the United States, residing at Gloversville, in the county of Fulton and State of New York, have invented a new, original, and ornamental Design for a Coin Purse, of which the following is a specification, reference being had to the accompanying drawing, forming a part hereof, wherein:

Fig. 1 is a perspective view showing one side of the coin purse with the frame members closed; and

Fig. 2 is a perspective view showing the other side of the coin purse with the frame members open.

I claim:

The ornamental design for a coin purse, substantially as shown.

WILLIAM H. ST. THOMAS.
